UNITED STATES PATENT OFFICE.

ALFRED COPONY, OF CHICAGO, ILLINOIS, ASSIGNEE TO WILLIAM H. MINER, OF CHICAGO, ILLINOIS.

PROCESS OF MAKING COMBINED CAST-STEEL AND WROUGHT-IRON YOKES.

1,128,296.

Specification of Letters Patent. Patented Feb. 16, 1915.

Application filed March 23, 1914. Serial No. 828,805.

To all whom it may concern:

Be it known that I, ALFRED COPONY, a subject of the Emperor of Austria-Hungary, residing in Chicago, in the county of Cook and State of Illinois, have invented a new and useful Improvement in Processes of Making Combined Cast-Steel and Wrought-Iron Yokes, of which the following is a specification.

10 This invention relates to improvements in process of making combined cast steel and wrought iron yokes.

An object of the invention is to provide a process or method involving few steps for 15 making a yoke for railway draft rigging, which yoke is composed partly of wrought iron straps and partly of steel castings all rigidly and permanently connected together.

The invention furthermore consists in the 20 novel steps and the novel combinations of the steps herein shown, described or claimed.

In the drawing forming a part of this specification, all the figures are perspective views.

25 Figure 1 shows one of the plain pieces of wrought iron which forms a part of the finished yoke. Fig. 2 shows the same strap of wrought iron with the ends thereof offset laterally and transversely relatively to the main central portion. Fig. 3 shows the strap bent into a substantially elongated U-shape. Fig. 4 shows a piece of wrought iron used to form the clip for connecting the two wrought iron straps of the yoke. Fig. 5 shows the clip-forming member after it has been notched. Fig. 6 shows the same member with the ends thereof elongated and reduced in thickness. Fig. 7 shows the clip-forming member after it is bent into U-shape 30 and as it appears before applied to the two wrought iron straps of the yoke. Fig. 8 shows the two bent wrought iron straps united by the clips. Fig. 9 shows one of the steel castings employed in the 35 yoke. Fig. 10 shows the two steel castings in position on the ends of the wrought iron members forming the arms and rear ends of the yoke and Fig. 11 illustrates the last step in the process and the 40 finished article wherein the ends of the straps are upset to secure the parts firmly together.

In said drawing 10 denotes a bar or strap of wrought iron cut into proper length.

This bar or strap then has its ends 11—11 offset laterally and transversely of the main portion 12 thereof after which it is bent into substantially elongated U-shape, as shown at 13 in Fig. 3. In this figure it will be seen that the offset portions 11 of the strap are brought closer to each other than the other horizontally extending portions 14, 14.

In Fig. 4 a piece of wrought iron 15 is shown which is employed to form the binding or connecting clip, said piece having rounded edges 16, 16. The member 15 is next cut or notched as at 17 to the form shown in Fig. 5. The ends 18 of the clip-forming piece are next forged and elongated, as shown in Fig. 6, after which the forged ends are bent at right angles to the main portion thereof as shown in Fig. 7, the clip or binding member now being in the form of a U.

Two wrought iron members are provided 75 for each yoke and are formed into the shape shown in Fig. 3. The same are then brought together side by side as shown in Fig. 8 and the U-shaped clip placed therebetween and the ends 19 of the clip bent over and around 80 the central portions of the yoke straps as shown at 20 in Fig. 8. Two steel castings are provided of the form shown in Fig. 9, each casting 21 being provided with two longitudinally extending slots 22, 22 and a transversely extending elongated slot 23. 85 The slots 22, 22 are adapted to receive the offset ends of the yoke arms and the steel castings are placed thereon as shown in Fig. 10. The extreme ends 24 of the wrought 90 iron straps are then hammered or upset as shown at 25, thereby permanently and rigidly connecting the steel castings to the wrought iron yokes, the latter of course being further united by the clip at the rear. 95

From the preceding description it will be seen that I have provided a combined cast steel and wrought iron yoke which is adapted to be used in a horizontal position and having slotted castings adapted to receive a 100 coupler connecting key through the slots 23. The process which I have devised for making the same consists of few and simple steps and may be carried out without the use of any expensive or complicated machinery. 105

I claim:—
The herein described process of making

combined cast steel and wrought iron yokes which consists in bending two wrought iron straps into substantially U-shape and laterally offsetting the ends of each strap whereby when said straps are placed side by side, the ends thereof are spaced apart; providing two slotted castings; and then inserting the ends of said straps in the slots of said

castings and upsetting the extreme ends of the straps.

Signed this 13 day of March 1914, in the presence of two subscribing witnesses.

ALFRED COPONY
